SHEET FEEDING MACHINES Headley Townsend Backhouse, Les Rayons,
Corsy-Conversion, Switzerland

Filed July 2, 1958, Ser. No. 746,136

Claims priority, application Great Britain July 8, 1957

3 Claims. (Cl. 271—60)

The invention relates to sheet feeding machines of the kind in which sheets are fed in succession (e.g. as a continuous stream of partly overlapping sheets) over a feed-table where registration of the front edge of each sheet in turn is obtained by engagement of the edge against one or more front lays which are then removed to enable the registered sheet to be removed to a printing or other machine operating on individual sheets. Side registration of the sheets may also be effected while on the feed table. The invention is concerned with improvements in the front lays and their operating mechanism is such a machine.

The invention provides a sheet feeding machine of the above kind embodying front lay mechanism comprising a front lay supported for rocking movements about an axis extending beneath the table horizontally and transversely to the feeding direction, from an upright operative position of the lay in which it projects above the table downwardly to an inoperative position in which it lies out of the path of a sheet being removed from the table, a rocker arm extending rearwardly beneath the table with at one end an operative connection to the lay for translating rocking movements of the arm into rocking movements of the lay, in at least one direction of the movement of the lay, and means operative on the other end of the arm for imparting rocking movement to the arm.

The invention also provides a sheet feeding machine of the above kind having a detachable front lay unit comprising a bracket with readily releasable means for attachment to the machine, a front lay supported by the bracket for rocking movements about an axis extending beneath the table horizontally and transversely to the feeding direction, from an upright operative position of the lay in which it projects above the table to an inoperative position in which it lies out of the path of a sheet being removed from the table, and lay-operating means carried by said bracket for co-operation with a constantly rotatable cam shaft forming a non-detachable part of the machine, for translating the rotational motion of the shaft into rocking movements as aforesaid of the lay.

The lay-operating means aforesaid may comprise a rocker arm as above described having at one end an operative connection to the lay and at the other end means for co-operating with the cam shaft for effecting the rocking movements of the arm.

In a preferred arrangement the bracket aforesaid constitutes a detachable and interchangeable section of a feed table or plate constructed substantially as described in British specification No. 777,432.

A specific construction of a sheet feeding machine embodying the invention will now be described, by way of example and with reference to the accompanying drawings in which:

Figure 1 is a simplified plan view showing one side of the feed table of the machine,

2

Figure 2 is a side view, partly broken away, of one of the front lay units, and

Figure 3 is a plan view, also partly broken away, of the front lay unit.

5 The machine forming the subject of this example has a feed table 10 over which sheets are fed from a conveyor, as a continuous stream, to front lays 11.

The feed table is constructed in sections 10a, 10b, 10c, 10d and 10e. The sections are supported on cross-bars 14, 15 and 16 secured at their ends in side frames 17.

10 The centre section 10d is fixed to the cross-bars whereas sections 10a and 10b are readily removable. The remaining sections (i.e. 10c and 10e) are slidable along the bars to different positions of adjustment. Accordingly, the effective width of the table and the number and separation of the front lays 11 may be varied.

15 The section 10e carries side-lay mechanism indicated diagrammatically at 18, the details of this mechanism forming no part of the present invention. The sections 10c, one at each side of the table, carry slow-down devices for slowing down the movement of the sheets before they contact the front lays 10. These devices are described in more detail in my specification Serial No. 746,147 filed July 2, 1958.

20 25 The machine as shown in the drawings has six sections 10a carrying front lays which are all of like construction and only one will be described. The section comprises a casting 20 which is of generally channel form. Within one end of the casting there is a bifurcated hook 21 which engages over the cross-bar 16

30 and near the other end there is an angle portion 22 which engages over the bar 14. A spring pressed plunger 23 engages the bar 14 and urges the section towards the right as viewed in Figure 2, this being in the direction against the movement of the sheets towards the lays. A plate 25 engages the underside of bar 14 and is secured to the casting. A screw 26 is engageable in any of a

35 number of holes 27 spaced along the bar 16 and serves not only to hold the section in its adjusted position along 40 the bar but also as a means for adjusting the position of the lays 11 in the direction of sheet movement. Thus, tightening of the screw will move the whole unit, including the lays, to the left, whereas on loosening of the screw the unit will be moved to the right by the action of plunger 23.

45 The lays 11 are carried at the ends of the arms 30 of a forked lever 31, the lever having a fulcrum 32. At the other end, the lever has a pivotal sliding connection 33 to a second lever 34. This lever has a roller 36

50 which runs on a constantly rotatable shaft 37, the shaft being supported in the side frames 17. The shaft is formed, along its length, with a flat 38 and accordingly acts as a cam which rocks the lever 34 which, in its turn, rocks lever 31 to raise and lower the lays 11. The lays 55 move downwardly from the position shown, until they lie beneath the level of the top of the table (i.e. below the top of the casting 20). A spring 39 operating through a plunger 40 effects upward movement of the connection 33 and the downward movement of the lays.

60 The unit also includes a detector for determining if no sheet is present at the lays at the proper time. This detector comprises a finger 45 which is located between the arms 30 and has near its upper end a hook 46. This hook is arranged for engagement with the upper surface of a projection 47 from the front of the casting 20.

65 The finger is pivoted to a lever 48 keyed to and slidable along a shaft 49. A spring 50 urges the hook 46 into position over the projection 47. When so positioned the upper end of the finger lies in front of the lays for engagement by a sheet. If a sheet arrives at the lays 70 at the correct time, it will push the finger back out of position for engagement of the hook with the projection

and the finger may be moved downwardly with the lays, this movement being effected by rocking motion of shaft 49. If, on the other hand, the finger is not moved by a sheet, then the hook will engage the projection and downward movement will be prevented. The effect will be that shaft 49 will not be rocked at the proper time and the trip or warning device will be operated in known manner. Furthermore screw 52 will prevent the lays from moving downwardly.

In use, the number of sections 10a and 10b appropriate to the width of the sheets being fed are employed. When there are more than two sections 10a all the front lays thereof may be used in alignment across the table or the outermost pair of lays may be positioned on the line of registration and the remainder set slightly behind that line to prevent excessive distortion of the edges of the sheets. It is one advantage of the construction described that in the event of a sheet failing to arrive at the proper time, the detector operates to retain the lays in their raised position and so to prevent a sheet which arrives late and when the lays would normally have been lowered, from overshooting the registering position.

I claim:

1. A sheet feeding machine comprising a feed table 25 over and across which sheets are fed in succession, a machine frame supporting the table, a constantly rotatable shaft which extends horizontally and transversely of the feeding direction of the sheets, is carried by said frame and is of non-circular cross-section over a substantial portion of its length thereby to constitute a cam and a front lay unit which is removable as such from the frame and comprises a bracket, readily releasable

5 means for attachment of the bracket to the machine frame, a front lay supported by the bracket for rocking movement about an axis extending beneath the table parallel to the said shaft from an upright operative position of the lay in which it projects above the plane of the table downwardly to an inoperative position in which it lies out of the path of the sheets leaving the table and lay-operating means carried by said bracket and arranged for co-operation with said cam for translating the rotational movement of the shaft into rocking movements as aforesaid of the lay.

10 2. A machine as claimed in claim 1 in which the lay-operating means comprise a rocker lever extending beneath the bracket and supported thereby for rocking movement about an axis located between and parallel to the shaft and the aforesaid rocking axis of the front lay and having at one end a connection to the lay operative to translate rocking movements of the lever into rocking movements of the lay and at the other end means 15 20 co-operating with the cam for effecting the rocking movements of the lever.

25 3. A machine as claimed in claim 1 in which the bracket is conducted to constitute a detachable section of the table surface.
